UNITED STATES PATENT OFFICE.

PAUL WINSOR, OF WESTON, AND CYRUS CORLISS, OF BOSTON, MASSACHUSETTS.

ELECTRIC COUPLING FOR CARS.

1,167,608.

Specification of Letters Patent.

Patented Jan. 11, 1916.

Application filed January 23, 1914. Serial No. 813,985.

To all whom it may concern:

Be it known that we, PAUL WINSOR and CYRUS CORLISS, citizens of the United States, and residents of Weston and Boston, in the 5 counties of Middlesex and Suffolk and State of Massachusetts, respectively, have invented an Improvement in Electric Coupling for Cars, of which the following description, in connection with the accompanying drawings, is a specification, like characters on the drawings representing like parts.

This invention relates to the automatic coupling of electric conductors or wires between cars, and has for its object to provide 15 proper electrical coupling terminals or heads at either or both ends of a car, so that when another car, similarly equipped, is connected thereto, the electrical conductors or wires on each car will automatically 20 be made continuous, irrespective of which end of either car is presented to the other.

The especial intention of the invention is to provide a means of arranging a plurality 25 of coupling contacts in such a way, that when the faces of any two of such pluralities are brought together, like circuits will be connected, the arrangement at each 30 end of each car always being identical with any other, and still doing away with the necessity of intermediate connections between the members for the purpose of connecting like circuits.

To this end, each or either end of a car 35 is provided with a coupling terminal, having a plurality of pairs of contact members, each pair of contacts being the terminal of one of the wires to be coupled, and the plane containing any pair of contacts being substantially parallel to the plane on which the 40 car is operated, with the members of each pair of contacts located on diametrically opposite sides of and substantially equi-distant from a line substantially at right angles to the aforesaid planes, said line being common 45 to all pairs of contacts.

The coupling terminals are carried by supports at the ends of the cars in such a manner that when two cars are coupled together, the pairs of contacts for corresponding 50 wires are in the same plane, and the above described lines for the coöperating pairs of contacts are coincident.

When cars so equipped are coupled as described, the contacts for corresponding 55 wires are in electrical contact, thereby mak-

ing like wires electrically continuous. The coupling terminals on the supports at the ends of the car when viewed from the opposite ends of the car, are exactly alike. These and other features of this invention 60 will be pointed out in the claims at the end of this specification.

Figure 1 is an elevation of the adjacent end portions of two railway cars coupled together and provided with coupling terminals embodying this invention. Fig. 2, a side elevation and section of the coupling terminals shown in Fig. 1. Fig. 3, a front elevation of one of the terminals shown in Fig. 2. Figs. 4 to 8, modified forms of 70 coupling terminals. Figs. 9 and 10 diagrammatic views to illustrate the circuit connections, and Fig. 11, an elevation of two cars with a modified form of support for the coupling terminals. 75

Referring to the drawing *a, b*, represent two cars of any suitable, usual or desired construction, such as now commonly used on elevated electric railway systems. The cars *a, b*, are provided with the usual draw 80 or coupling bars *c, d*, both of which in the present instance project beyond the ends 10, 12 of the cars and form supports for coupling terminals *e, f*, by which the conductors or wires on one car are connected with like 85 wires of the other car.

Each of the coupling terminals *e, f*, is provided with a plurality of contact members, which have certain parts located in a plane substantially parallel with the plane on 90 which the car travels, and on substantially diametrically opposite sides of and substantially equi-distant from a line substantially at right angles to the first mentioned plane.

For sake of clearness, the plane in which the members of a pair of contacts are located, may be designated the horizontal plane, and the line from which the members of said pair are equi-distant may be designated the vertical line. The coupling members *e, f*, may be provided with various forms of contact members. In Figs. 2 and 3, the contact members are represented as movable and rigid, that is, the movable member is shown as a plunger 13, backed up by a spring 14, and the rigid member is shown as a block 15.

In Fig. 3, the terminal member *e* is shown as provided with five pairs of movable and rigid members 13, 15, with the movable and 110

rigid members of each pair located in the same horizontal plane and equi-distant from a vertical line 16.

The members 13, 15 of each pair are electrically connected by a conductor, and the conductors connecting the members of the five pairs of contacts are numbered 17, 18, 19, 20, 21. The movable and rigid members 13, 15 of the coupling terminal *f*, are arranged in pairs and connected in a like manner, but are arranged so that when coupled with the terminal *e*, the contact members of terminal *f* are reversed to the contact members of terminal *e*. Each car is provided at one end with a coupling terminal *e* and at its opposite end with a coupling member *f*, so that when one end of the car as *a* is coupled to the other car *b*, the terminal *e* coöperates with the terminal *f*, and when the car *a* is reversed and its opposite end is coupled to the car *b*, the coupling terminal *f* on the car *a* will couple with the terminal *f* on the car *b*, as clearly shown in the diagrammatic Figs. 9 and 10. In Fig. 9, two pairs of contact members of each terminal *e*, *f*, are shown, and it will be observed that when the contact members of the terminals *e*, *f*, are viewed by a person looking toward the ends of the car, both pairs of contact members are arranged exactly alike, and when the contact members of each pair are different in construction, as represented in Figs. 2, 4, and 6, the contact members of one terminal as *e* are reversely arranged with relation to the contact members of terminal *f*, when considered with relation to the longitudinal center of the car, but are exactly alike when looked at from the opposite ends of the car. The reversal of contact members with respect to the longitudinal center of the car, is especially noticeable when male and female contact members are used. In Fig. 9, the contact members of the terminal *e* on car *a* are supposed to make contact with the contact members of terminal *f* of car *b*, and in Fig. 10, the car *a* is supposed to be reversed and terminal *f* thereof engages terminal *f* of car *b*. The members 13, 15 of the coupling terminals may be of any desired construction, and the contact members of the various pairs of contacts may be arranged with both movable and rigid members on both sides of the vertical plane 16, as represented in Fig. 3, or all the movable members may be arranged on one side of said plane and all the rigid members on the other side of said plane as represented in Figs. 4 to 7. In Figs. 4 and 5, the members 13 are shown as plugs, and the members 15 as sockets, and in Figs. 6 and 7, the members 13 are shown as springs and the members 15 as flat strips.

In Fig. 8, the contacts 13, 15 are of like construction and are represented as abutting contact members, which are formed by the

opposite ends of bent metal strips. In the arrangement shown in Fig. 8, three bent metal strips are shown, which correspond to the connecting wires 17, 18, 19 of the arrangement shown in Fig. 3, and the opposite ends of said metal strips correspond to the members 13, 15 of the arrangement shown in Fig. 3, and are thus numbered. In the arrangement shown in Figs. 2 and 3, five pairs of contacts are shown and their connecting wires 17 to 21 inclusive are connected to five wires 25, 26, 27, 28, 29, which are electrically connected to the other terminal *f*.

In Figs. 4 and 5, seven pairs of contact members and seven line wires are shown. In Figs. 6 and 7, six pairs of contact members and six line wires are shown, and in Fig. 8, three pairs of contact members and three wires are shown.

In Fig. 1, the bars *c*, *d*, which serve to couple the cars together are shown as constituting the supports for the coupling terminals, and it will be seen that when the coupling bars *c*, *d*, are coupled together automatically as commonly practised, the terminals *e*, *f*, carried thereby are automatically connected, which dispenses with the flexible cable or jumper now commonly employed, and also avoids the necessity of effecting the electrical connection of one car with another by manual labor. It may be preferred to employ the coupling bars *c*, *d*, as the supports for the coupling terminals, but it is not desired to limit the invention in this respect, as the supports for the coupling terminals may be otherwise located, as for instance, as shown in Fig. 11, wherein the supports for the terminals *e*, *f*, are shown as located above the cars *a*, *b*, and are suitably constructed to provide for up and down, horizontal and longitudinal movements. To this end, the supports are shown as levers or arms *h*, *i*, pivoted at *j*, *k*, to rods *m*, *n*, which slide in tubes, *o*, *p*, pivoted at *q*, *r* to the roofs of the cars. The rods *m*, *n* are capable of sliding in the tubes *o*, *p* and are backed up in a manner well understood by helical springs *W*, to provide for the longitudinal movement of the supports, and the pivots *k*, *j*, take care of the vertical movement thereof, while the pivots *q*, *r* provide for the horizontal movement. The supports are provided with suitable means shown as lugs or fingers *s*, *t*, which gather and center the said supports, when the cars are coupled together.

The wires connecting the terminals *e*, *f*, may and preferably will be provided in practice with a suitable switch, not shown, for rendering the terminals dead, when the cars are to be uncoupled.

Claims—

1. The combination with a car provided with wires or electrical conductors, of elec-

- trical coupling terminals carried by and located at the opposite ends of said car, each of said coupling terminals having a plurality of pairs of contact members, with the 5 contact members of each pair connected electrically together and to a single electrical conductor, a plurality of said pairs being located in the same plane with the members of each pair on opposite sides of a 10 plane at right angles to the said plane and with both members of each pair equi-distant from said latter plane, whereby the car can be coupled directly at either end with another car, equipped exactly the same, and 15 connect like electrical conductors in one car with the same electrical conductors in the other car or cars irrespective of which ends of the cars are coupled together.
2. The combination with a car provided 20 with wires or electrical conductors, of electrical coupling terminals carried by and located at the opposite ends of said car, each of said coupling terminals having a plurality of pairs of contact members, with 25 the contact members of each pair connected
- electrically together and to a single electrical conductor, the contact members of some of the pairs being separated by different distances, with the members of each pair on opposite sides of a plane common to all the 30 pairs and at right angles to the planes in which the contact members of each pair are located, and with both members of each pair equi-distant from said latter plane, whereby when two cars equipped identically are 35 coupled together, each electrical conductor in the coupling terminal will be automatically connected to exactly the corresponding electrical conductor in the coupling terminal of the adjacent car irrespective of which 40 ends of the cars come together.

In testimony whereof, we have signed our names to this specification in the presence of two subscribing witnesses.
